UNITED STATES PATENT OFFICE

MAURICE M. STRAUSS, OF CHICAGO, ILLINOIS.

COMBINED SHIPPING-PACKAGE AND HANGER FOR GARMENTS.

No. 888,201.

Specification of Letters Patent.

Patented May 19, 1908.

Application filed January 5, 1905. Serial No. 239,765.

To all whom it may concern:

Be it known that I, MAURICE M. STRAUSS, a citizen of the United States, and a resident of Chicago, county of Cook, and State of Illinois, have invented certain new and useful Improvements in Combined Shipping-Packages and Hangers for Garments, of which the following is declared to be a full, clear, and exact description.

- 10 The improvement relates to shipping packages and holders for garments and particularly for trousers, and seeks to provide an inexpensive package in which trousers and the like can be shipped without wrinkling and which can also be used as a garment holder.
- 15 The invention consists in the features of construction and arrangement of parts hereinafter set forth, illustrated in the accompanying drawings and more particularly 20 pointed out in the appended claims.

In the drawings, Figure 1 is a plan view of the improved package. Fig. 2 is a view of the same with the cover removed. Fig. 3 is a plan view of the box section of the package. Fig. 4 is a longitudinal section of the package. Fig. 5 is an enlarged section of part of the box bottom and Fig. 6 is a view of the box bottom as changed to form a garment holder.

The improved package is formed of heavy 30 paper board and comprises a box section 10 and a cover section 11 adapted to snugly fit over the box-section. The box and cover sections are preferably collapsible and formed of blanks of paper board scored on the lines 35 *a* to form the straight foldable ends 12 and sides 13. Each side and end piece is provided at one end with a foldable tongue 14 adapted to interlock with or engage a slot 15 in the end of the adjacent side or end piece. 40 The box section is illustrated in detail in Fig. 3. It will be understood that the cover section is similarly constructed but is slightly larger to fit snugly over the box section.

The straight ends of the box and cover sections are parallel and one straight side is arranged at right angles to the ends, while the opposite straight side is inclined thereto so that the box is wider at one end than the other, and the box as a whole is so shaped as 50 to receive a pair of trousers once folded, as indicated, or with bottom end of the trousers turned in to a slight extent. Moreover, the end and side pieces 12 and 13 are narrow so that the box and cover sections are shallow 55 and are each less in thickness than the folded pair of trousers, as indicated in Fig. 3. The

trousers are once folded and placed flat in the shallow box section 10, the cover section 11 is placed over the box section and the two sections of the package tied together with string, 60 as indicated in Fig. 1. Inasmuch as the box and cover sections are less in thickness than the folded pair of trousers, the latter will be snugly held in smooth, flat condition and will not be wrinkled during transportation, even 65 if the packages are roughly handled. With packages now in use, trousers and other garments must be pressed when received after shipment before they can be worn.

One of the separate sections of the pack- 70 age, preferably, the bottom or box section, is provided with a detachable elongated portion 16, formed by scoring or partially cutting through the bottom of the box on the lines *b*, so that when the portion 16 is re- 75 moved, an elongated cross slot is formed through which the trousers are passed when the box portion is used as a holder.

A reinforcement 17 of paper board, pasted or otherwise cemented to the inner face of 80 the bottom of the box 10, is provided with an elongated cross slot 18 in line with the removable portion 16. One end of the reinforcement is provided with a suitable hanging device by which the box section may be 85 supported in vertical position with the trouser-supporting slot horizontally disposed. In the form shown, the hanger comprises a loop 19 of tape passed through a hole 20 in the reinforcement. Preferably, the 90 upper end of the reinforcement 17 is provided on opposite sides of the hanger 19 with inclined shoulder-engaging portions *c*, and preferably also, the box bottom 10' is 95 scored or partially cut through as at *d* in line with the inclined shoulder engaging portions *c*, so that the sections 21 of the box bottom 10', are easily removable.

The recipient of the package may easily remove the ends and sides 12 and 13 and the 100 portions 16 and 21 of the box, since the latter is scored or partially cut through along the lines *a*, *b* and *d*, so that a garment hanger, such as indicated in Fig. 6, is formed, and upon which the trousers, together with a 105 coat or other garment, may be hung up in smooth, un wrinkled condition.

It is obvious that the details of construction may be varied without departure from the essentials of the invention as set forth in 110 the claims.

Having described my invention, what I

claim as new and desire to secure by Letters Patent is:

1. A combined shipping package and garment holder comprising separate box and cover sections of paper board, one of said sections having easily removable side and end walls and having a reinforcement of paper board cemented to the inner face thereof, said reinforcement having inclined shoulder-engaging portions at one end and a cross-slot below said shoulder-engaging portions and a hanging device connected to the shoulder-engaging end of said reinforcement, substantially as described.
2. A combined shipping package and garment holder comprising separate box and cover sections of paper board, one of said sections having a reinforcement of paper board cemented to the inner face thereof,

said reinforcement having an elongated cross-slot therein and said package-section having an easily removable portion opposite said slot, substantially as described.

3. A combined shipping package and garment holder comprising separate box and cover sections of paper board, one of said sections having a reinforcement of paper board cemented to the inner face thereof, said reinforcement having inclined shoulder-engaging portions at one end and a cross-slot below said shoulder-engaging portions, and said package section being scored in line with said shoulder-engaging portions and said slot, substantially as described.

MAURICE M. STRAUSS.
